UNITED STATES PATENT OFFICE.

THEODORE P. BROWN, OF WORCESTER, MASSACHUSETTS, ASSIGNOR TO SIMPLEX PIANO PLAYER CO., OF WORCESTER, MASSACHUSETTS, A CORPORATION OF MASSACHUSETTS.

DESIGN FOR A PIANO-CASING.

40,559.

Specification for Design.

Patented Mar. 1, 1910.

Application filed February 10, 1909. Serial No. 477,255. Term of patent 14 years.

To all whom it may concern:

Be it known that I, THEODORE P. BROWN, a citizen of the United States, residing at Worcester, in the county of Worcester and State of Massachusetts, have invented a new, original, and ornamental Design for a Piano-Casing, of which the following is a specification, reference being had to the accompanying drawing, forming part thereof,

in which the figure is a perspective view of a piano-casing showing my new design.

I claim:

The ornamental design for a piano casing as shown.

THEODORE P. BROWN.
